UNITED STATES PATENT OFFICE.

MAURICE ALLAND, OF ATLANTIC CITY, NEW JERSEY.

POCKET-GOLF GAME.

Application filed January 10, 1928. Serial No. 245,673.

The object of the invention is to provide an improved game which resembles the well-known game of golf in that a ball is manually propelled into a hole, and it is the general object of the game to get the ball into the hole in a single stroke if possible, or in as few more strokes as may become necessary.

Another object is to so construct the device that a simple and efficient means for keeping the score is incorporated as a unitary part of the same, and so arranged that it does not interfere even to the slightest degree with the manipulation of the article when the game is being played.

Still another object is to provide in a device of this character a propelling means, which becomes automatically reset when the device as a unit is tipped upwardly into the position in which the ball, having been played and having entered a pocket other than the hole for which it was intended, is returned by gravity towards the original playing position.

A further object is to construct a device of this character so as to comprise a cylindrical casing with a transparent closure for one end or face thereof, a closure for the opposite face or bottom of said casing which may comprise a mirror, and a false bottom upon which the plays are made and which is cut away at one point, so as to form a pocket of which said second closure forms the bottom.

With these and other objects in mind, the present invention comprises further details of construction and operation such as are fully brought out in the following description, when read in conjunction with the accompanying drawings, in which Fig. 1 is a vertical diametrical section of one embodiment of the invention taken on the line 1—1 of Fig. 2; Fig. 2 is a top plan view of the same, but of smaller dimensions; Fig. 3 is a bottom plan view of the same; Fig. 4 is an enlarged fragmentary detail; and Figs. 5 and 6 are respectively side and end elevations of the propelling mechanism for the ball or other form of player.

Referring to the drawings, the invention comprises a cylindrical casing 1, one marginal edge of which is inturned to provide a flange 2, against which rests a transparent closure 3, while the other end of said casing is inturned at 4 to provide a rest for a bot-

tom wall or closure 5, which, if desired, may 55 comprise a mirror, picture, or the like.

Within said casing there is positioned a cylindrical member 6, one end of which is closed by a bottom 7, which, however, together with the marginal portion of said last-named portion, is cut away through a given region 8 to provide a pocket 9, while the bottom 7 is also provided with an aperture 10 which represents the usual hole in a putting green of a golf course. The pocket 9 is provided with a suitable lining 11 upon the normally upper or inner surface of the second closure 5 and the bottom 7, which represents the usual putting green, is covered by any suitable layer 12 of crepe paper, plush, or 70 other material which will on a small scale resemble the grass of a putting green.

Diametrically opposite to the pocket 9 the inner cylindrical member 6 is provided with an aperture 13 which extends radially outwardly and opens into a keyway or the like 14, in which is positioned the disc-like flange 15 of the projecting mechanism shown in Figs. 5 and 6. This mechanism further comprises a cylindrical body portion 16 to which 80 the flange 15 is integrally connected, and in the opposite direction with a reduced end portion 17, adapted to receive and swedged to receive and retain thereon a washer or collar 18.

The body portion 16 is also provided with an enlarged bore 19, extending axially inwardly from one end and normally in alignment and communicating with the aperture 13 in the member 6, said bore thence merging 90 into a second bore 20 of reduced diameter, adapted to receive in slidably engagement a shank 21, which is provided with a head 22 movable within the enlarged bore 19 and also upon its opposite end with a removable actuating knob or head 23.

Surrounding the body 16 of said actuating mechanism is a plurality of rotatable discs 24, upon the periphery of each of which there are formed in any suitable manner numerals or other indicia for the purpose of keeping the score. If desired, a third rotatable disc 25 may also surround and move with respect to said propelling mechanism and may bear letters or other indicia for identifying the several persons using the device, that is, playing the game.

With a construction such as thus described,

the device as shown in Fig. 1 is tilted upwardly so that the ball 26 within said casing rolls by gravity towards and extends slightly into the aperture 13, the propelling member 21 being moved by gravity into the position shown with the head 22 withdrawn to the innermost limit of the bore 19. The operating head or knob 23 is touched or struck sharply by the finger of a player so that the head 22 strikes the ball 26 with the idea of propelling the latter into the hole 10 in a single stroke if possible. If the ball instead of entering said hole rolls short, the device is tilted so that the ball returns to the aperture 15 and seat 13 and the propelling member returns to its outer position. Upon striking the propelling mechanism again, the ball may pass beyond the hole 10 and enter the pocket 9, in which case the device is tilted 20 even further than previously so that by gravity or a slight tap upon the glass or similar closure 3, the ball is dislodged from the pocket 9 and returned by gravity to said seat and the propelling mechanism automatically returned by gravity to its initial position.

As a given player, represented for instance by A on the disc 25, plays the game, he may require twelve strokes before he is able to get the ball into the hole. The object thereafter is 30 for each succeeding player to reduce if possible the number of strokes necessary to hole the ball. Thus, if player B is unable to reduce the number of strokes, A's score of twelve remains, but if C is finally able to hole the ball is eight strokes, for instance, the disc 25 is rotated so as to bring C uppermost and with his score of "08" shown upon the discs 24 opposite his letter.

The foregoing method of playing the game 40 is one way in which the device may be used, but it will be readily understood that different persons will have different ways in which they may desire to carry out the same, although in each instance the actuation of 45 the propelling mechanism and the game as a whole will be the same.

Having thus described my invention, what I claim and desire to protect by Letters Patent of the United States is:—

50 1. A game, comprising a casing having a bottom provided with a recess, and provided

at one side with an aperture seat, a casing for a propelling member secured to said first casing in alignment with said aperture, a reciprocatory member movable in said second casing and adapted to strike and impel a ball positioned in said seat towards said recess, and a disc bearing indicia and rotatably carried by said second casing to indicate the number of times said propelling mechanism is actuated in placing the ball in said recess. 55 60

2. A game, comprising a casing having a transparent closure on one end, a closure for the opposite end, a false bottom having a recess and cut away at one point to provide 65 a pocket having said second closure as a bottom, an aperture in a wall of said casing to provide a seat for a ball, and propelling means to actuate said ball towards said recess and into said pocket if said recess is 70 missed.

3. A game, comprising a casing having a transparent closure on one end, a closure for the opposite end, a false bottom having a recess and cut away at one point to provide 75 a pocket having said second closure as a bottom, an aperture in a wall of said casing to provide a seat for a ball, a second casing, means to secure said last-named casing to said first casing, and reciprocatory propelling 80 means slidably mounted in said second casing and operative when manually impelled to move a ball from said seat towards said recess.

4. A game, comprising a casing having a transparent closure on one end, a closure for 85 the opposite end, a false bottom having a recess and cut away at one point to provide a pocket having said second closure as a bottom, an aperture in a wall of said casing to provide a seat for a ball, a second casing, 90 means to secure said last-named casing to said first casing, reciprocatory propelling means slidably mounted in said second casing and operative when manually impelled to move a ball from said seat towards said recess, and discs bearing indicia and rotatably carried by said second casing, to indicate the number of movements of said propelling means necessary to place the ball in the said recess. 95

In testimony whereof I have affixed my 100 signature.

MAURICE ALLAND.
